SPRINGLESS ELECTRIC PUSH-BUTTON SWITCH

Nickolas A. Matheis, St. Paul, Minn.

Application November 19, 1948, Serial No. 61,020

2 Claims. (Cl. 200—159)

1

This invention relates to a novel push button type switch especially adapted for use on audible or visual signals such as door bells, call bells and signals and has for a primary object to provide a push button type switch of extremely simple construction which utilizes no springs for normally retaining the push button switch in a circuit interrupting position.

Another object of the invention is to provide a push button which will function when mounted in any position.

Various other objects and advantages of the invention will hereinafter become more fully apparent from the following description of the drawings, illustrating a preferred embodiment thereof, and wherein:

Figure 1 is an elevational view looking toward the outer side of the push button;

Figure 2 is an elevational view thereof taken at right angles of Figure 1;

Figure 3 is a central sectional view taken substantially along a plane as indicated by the line 3—3 of Figure 1;

Figure 4 is an elevational or plan view of the internal parts of the push button switch with certain of the elements thereof removed;

Figure 5 is a sectional view taken substantially along a plane as indicated by the line 5—5 of Figure 1;

Figure 6 is a plan view of one element of the device;

Figure 7 is a plan view of another element thereof;

Figure 8 is a diagrammatic view illustrating the electric circuit of the switch, and

Figure 9 is an edge elevational view, partly in section of another part of the device.

Referring more specifically to the drawings, the novel push button switch comprising the invention is designated generally 10 and includes a mounting plate 11 having laterally spaced openings 12 and 13 for receiving wood screws 14 and 15 by which the plate 11 is secured to a supporting surface 16 such as a door jamb. The screw 14 carries a washer 17 of electrical insulating material by means of which said screw is insulated from the plate 11, for a purpose which will hereinafter become apparent.

As best seen in Figure 4, a strip 18 of electrical conducting material is disposed across a portion of the mounting plate 11 and is secured thereto by screw fastenings 19 and also by the anchoring screw 15 which extends therethrough. The upper portion of the mounting plate 11 is provided with an opening 20 which registers with a bore 21

2

of the door jamb 16 and through which extends two electrical conductors 22 and 23 which are covered with electrical insulation except at their terminals which are provided with metal eyes 24 and 25, respectively, through which the screws 14 and 15, respectively, extend. The edge portion of the plate 11 is provided with struck-out tongues 26 under which the wires 22 and 23 pass and which hold said wires away from the central portion of the plate 11, for a purpose which will hereinafter become apparent.

A leaf or plate 27 is swingably connected to a portion of the upper edge of the strip 18 by a hinge 28 and has a plate 29 secured to its outer side by fastenings 30a. The plate 29 has integral depending end portions forming weighted arms 30 which are normally disposed substantially parallel to the mounting plate 11, as seen in Figure 3 and for positioning the plates 27 and 29 in upwardly diverging relationship to the upper portion of the mounting plate 11.

The lower portion of the mounting plate is provided with integral struck-up ears 31 having aligned apertures 32 for receiving the ends of a pivot pin 33 which extends through the lower portion of a lever 34, which lower portion is disposed between the ears 31. The intermediate portion of the lever 34 is provided with a laterally opening recess 35 for receiving a nut 36 which is secured to a screw 37 which extends through the inner portion of the lever 34 and the head of which is disposed on the inner side of said lever. An electrical conductor 38 which is covered with electrical insulating material has a conductor eye 39 on one exposed end thereof which is mounted on the shank of the screw 37 and against the head thereof and said conductor extends downwardly therefrom between the mounting plate 11 and lever 34 and through a notch 40 in one of the ears 31. The exposed opposite end of the conductor 38 is likewise provided with a conductor eye 41 which is mounted on the screw 14 and in electrical contact with the eye 24. The inner surface of the upper, free end of the lever 34 is inwardly bowed in a longitudinal direction and bears against the upper edge of the plate 29, as best seen in Figure 3.

The outward swinging movement of the lever 34 is limited by a concavo-convex cover 42 which is detachably disposed over the parts previously described and the concave inner side of which is adapted to accommodate said parts. The cover 42 is provided with an annular inwardly inclined flange 43 having spaced openings for receiving wood screws 44 which are anchored in surface 16

for detachably mounting the cover. The central portion of the cover 42 is provided with an opening 45 for loosely receiving an integral outwardly projecting extension 46 of the intermediate portion of the lever 34 which extends loosely through said opening 45 and which is preferably substantially hemispherical and forms a manually engageable push button which is adapted to be pressed inwardly of the cover 42 for swinging the lever 34 inwardly for closing the electric circuit of the push button switch 10.

Assuming that the opposite ends of the conductors 22 and 23 are connected to a source of electric current and also to an audible or visual signal, not shown, it will be readily apparent that when the projection or button 46 is pushed inwardly, the lever 34 will swing inwardly to cause the head of the screw 37 to contact the conductor strip 18 so that current will flow through said strip between the conductors 23 and 38 and since the conductor 38 is connected directly to the conductor 22 at the screw 14, the switch 10 will thus be disposed in a circuit closing position. Likewise, when the lever 34 is thus rocked inwardly the hinge plates 27 and 29 will be swung inwardly on the hinge 28 toward the mounting plate 11 from their full line to their dotted line positions thus causing the weighted arms 30 to swing outwardly from the plate 11, likewise from their full line to their dotted line positions of Figure 3. The weight of the arms 30 is considerably greater than that of the lever 34 so that when pressure on the button 46 thereof is released, the weights 30 will swing downwardly and toward the mounting plate 11 and back to their full line positions of Figure 3 causing the upper edge of the plate 29 by a camming engagement with the inner edge of the upper portion of the lever 34 to return said lever to its full line position of Figure 3 or to cause the lever 34 to swing clockwise on its pivot 33 away from the mounting plate 11 and so that the head of the bolt 37 will be moved out of engagement with the strip 18 to thus interrupt the circuit through the switch 10. The lever 34 is formed of an electrical insulating material.

While the invention has been illustrated and described as mounted on an upright or vertical supporting surface, it will be readily apparent that it will function equally as well when mounted on the upper side of a horizontal surface since the weighted arms 30 are sufficiently heavy to raise the lever 34 for breaking the circuit or the push button switch may be mounted on the under side of a horizontally disposed surface in which case the weight of the lever member 30 will return it to a circuit interrupting position.

Various modifications and changes are contemplated and may obviously be resorted to, without departing from the spirit or scope of the invention as hereinafter defined by the appended claims.

I claim as my invention:

1. A push button switch comprising a mounting plate, a stationary electric contact fixed thereto, a swingably mounted member pivotally supported at one of its ends on the mounting plate, a movable electric contact carried by said swingably mounted member for movement therewith into and out of engagement with the stationary contact, a gravity responsive member swingably supported on the mounting plate and normally assuming a position against the mounting plate, and an element projecting obliquely from said gravity responsive member for sliding engagement with the swingably mounted mem-

ber, adjacent its free end, for normally holding the swingably mounted member in a position whereby the movable contact, carried thereby, is out of engagement with the stationary contact when the mounting plate is supported in either a horizontal or a vertical plane, said gravity responsive member comprising a pair of depending weighted arms disposed to straddle the swingably mounted member when the latter is moved toward a circuit closing position, said element of the gravity responsive member comprising a plate to which said weighted arms are connected, said plate being hingedly connected to the mounting plate and disposed at an oblique angle to the weighted arms to extend upwardly and outwardly relatively to the mounting plate when the arms are in a normal position against the mounting plate, and the free edge of said last mentioned plate engaging a portion of said swingably mounted member for urging the member away from the mounting plate.

2. A push button switch comprising a mounting plate, a stationary electric contact fixed thereto, a swingably mounted member pivotally supported at one of its ends on the mounting plate, a movable electric contact carried by said swingably mounted member for movement therewith into and out of engagement with the stationary contact, a gravity responsive member swingably supported on the mounting plate and normally assuming a position against the mounting plate, and an element projecting obliquely from said gravity responsive member for sliding engagement with the swingably mounted member, adjacent its free end, for normally holding the swingably mounted member in a position whereby the movable contact, carried thereby, is out of engagement with the stationary contact when the mounting plate is supported in either a horizontal or a vertical plane, said gravity responsive member comprising a pair of depending weighted arms disposed to straddle the swingably mounted member when the latter is moved toward a circuit closing position, said element of the gravity responsive member comprising a plate to which said weighted arms are connected, said plate being hingedly connected to the mounting plate and disposed at an oblique angle to the weighted arms to extend upwardly and outwardly relatively to the mounting plate when the arms are in a normal position against the mounting plate, the free edge of said last mentioned plate engaging a portion of said swingably mounted member for urging the member away from the mounting plate, a detachable cover for enclosing said parts having an opening therein, and a projection on said swingably mounted member extending reciprocally through said opening and forming a manually engageable push button.

NICKOLAS A. MATHEIS.
